UNITED STATES PATENT OFFICE.

JAMES F. RALEIGH, OF RIVER FOREST, ILLINOIS, ASSIGNOR TO PINES WINTER-FRONT COMPANY, OF CHICAGO, ILLINOIS, A CORPORATION OF DELAWARE.

THERMOSTATICALLY-CONTROLLED RADIATOR SHUTTER FOR AUTOMOBILES.

Application filed March 16, 1925. Serial No. 16,089.

My invention relates to thermostatically controlled radiator shutters for automobiles.

One of the principal objects of the invention is to provide improved means for housing or mounting the thermostatic element or elements in such manner that access thereto can be easily obtained for substituting these elements or for adjusting the same. It frequently happens that the thermostatic means is too responsive or is insufficiently responsive for proper thermal control of the automobile cooling system, and to correct this condition the thermostatic means is usually substituted or adjusted. Heretofore, this substitution or adjustment has necessitated the disassembly of a considerable part of the entire shutter device, in order to gain access to the thermostatic means. This is avoided in the present shutter device by the provision of an improved closure element or holder by the releasing of which access can be gained to the thermostatic means without disassembly of any part of the shutter device.

A further object of the present invention is to provide means for improving the heat conductivity between the radiator and the thermostatic element or elements of the shutter device. This improved means affords a more extended surface and a more intimate contact with the radiator core for transferring heat from the core to the thermally responsive means of the shutter device. This improved heat transfer means has particular application to certain types of radiators, where the necessary heat transfer to the thermostatic means is difficult to obtain.

Further objects will appear from the following description of a preferred embodiment of my invention.

In the accompanying drawing illustrating this embodiment:

Figure 1 is a vertical sectional view through the upper portion of a shutter device embodying my invention, the adjacent portion of the automobile radiator being also shown in section;

Figure 2 is an elevational view of the mounting plate with the releasable closure element or holder mounted therein as viewed from the rear side of the shutter device;

Figure 3 is a substantially similar view

of the mounting plate with the holder and closure element removed, and

Figure 4 is a perspective view of the closure and holder element.

Figure 5 is a vertical sectional view taken on the plane represented by the line 5—5 of Figure 1.

Referring to Fig. 1, a portion of an automobile radiator is represented by the upper water box 7 and the series of circulating tubes 8. The shutter device 9 comprises a series of shutters 11 which control the flow of air past the radiator tubes 8. These shutters are generally controlled or actuated by thermostatic means which I shall presently describe.

As illustrative of a practical application of my invention, I shall describe the same as embodied in a radiator shutter device of the type disclosed in my prior Patent No. 1,458,593. Shutter devices of this type generally consist of two major units, namely, the frame 12 in which are mounted the shutters 11, and the fenestrated shield or shell 13 in which the frame 12 is mounted. This construction permits of the use of a standardized frame assembly for practically all cars, the shield or shell 13 being merely substituted for the different designs and sizes of radiators. For the details of this construction, attention is directed to my above-mentioned prior patent. The frame 12 is represented in part by the channel member 12', and the outer shell is represented by the cup-shaped covering portion 13'. The frame member 12' extends from side to side of the frame and has bolted thereto a mounting plate 15, shown in elevation in Figs. 2 and 3. This mounting plate has ears 16 having bolt holes 17 for receiving bolts 18, by which the plate is fastened to the channel frame member 12'. Secured to the front of the mounting plate 15 by additional bolts 18 is a cup-shaped housing 21. A cup-shaped wood block 20 is preferably interposed between this housing 21 and the cup-shaped portion 13' of the outer shell for additional heat insulation between the two. The connecting bolts 18 pass through aligned apertures in the mounting plate 15 and in the flanged periphery of the housing member 21, receiving nuts 19 on the front side of the

housing flange, as shown in Fig. 1. A gasket 22 of heat insulating material is preferably interposed between the flange of the housing 21 and the mounting plate 15 to minimize the conduction of heat to the insulating member 21. This heat insulating gasket is preferably of the same shape as the mounting plate 15, including the ears 16 and is extended down to lie between the 10 flange 23 of the frame channel 12' and the mounting plate 15.

Defined between the mounting plate 15 and the cup-shaped housing 21, or between this mounting plate and the front shell 13', 15 is a chamber 24 in which is housed the thermostatic means. For this embodiment of shutter device the thermostatic means preferably comprises two or more thermowafers 25, each consisting of a hollow sheet metal 20 shell having flexible side walls. Each wafer contains a gas or liquid having a high coefficient of expansion and contraction, such as ether. A typical construction of thermo-wafer is disclosed in my copending application Serial No. 16,090, filed March 16, 1925. The outer wafer of the series bears against a pallet 26 which has pivotal connection with a crank portion 27 formed in the vertical operating rod 28. This operating rod 25 is pivotally supported in the housing member 21 and has suitable operative connection with the shutters 11, the details of which operative connection need not be described here, as they constitute no part of the present invention.

As before described, these thermowafers cells are oftentimes too responsive, or are insufficiently responsive, for proper operation of the shutter device, resulting in insufficient heating or in overheating of the 40 cooling system. This is only ascertained after the shutter device has been completely assembled and mounted on the radiator. This condition is generally corrected by substituting wafer cells having a greater or lesser content of ether for obtaining a quicker or slower response to temperature change. Heretofore the substitution of different thermowafers has involved considerable labor and expense. After removing the shutter device from the radiator, the outer shell had to be separated from the frame 12 to afford access to the nuts 19. This separation of the shell 13 and frame 12 necessitates the release of several points of attachment between the two. After separating these two main elements, the nuts 19 must all be released and the bolts 18 all withdrawn to separate the mounting plate 60 15 from the frame 12, before access can be had to the thermowafers 25.

According to the present invention, I avoid these difficulties by providing a readily releasable closure element for the rear 65 end of the chamber 24, through which ac-

cess can be gained to the thermowafers for their substitution or adjustment, without necessitating the separation of the shell and the frame or any of the other steps outlined above. A circular hole 31 is provided in the 70 mounting plate 15 through which the thermowafers can be withdrawn from the chamber 24. Segmental portions of the plate around the margins of this hole are punched back to form arcuate keys or locking lugs 32. The metal remaining in the 75 plane of the plate 15 between these arcuate keys forms cooperating arcuate keys 33. The corresponding end of each key 33 is punched backwardly to form a sloped locking 80 surface 34.

Supported in this opening 31 is a combined closure element and wafer holder 36. This unit consists of a sheet metal cup preferably of aluminum for high heat conductivity, having an annular wall 37 and a rear end wall 38. The annular wall 37 confines and supports the thermowafers 25, and the end wall 38 functions as a rear abutment for the wafers and as a heat absorbing surface 90 for conducting heat to the thermowafers. Projecting from the periphery of the holder 36, adjacent the rear wall 38, is a plurality of arcuate keys 39 which are adapted to have interlocking engagement with the keys 32 and 33. The keys 39 are preferably formed by compressing the cup-shaped blank longitudinally in dies which permit the metal adjacent the end wall to expand outwardly to the diameter of the keys 39. 100 Segmental portions of this expanded metal are then removed to form the keys 39. In mounting the holder in the mounting plate 15, the thermowafers 25 are assembled in the holder, and the holder is then inserted 105 into the opening 31, the keys 39 being first placed in register with the keys 32 and being then revolved into interlocking engagement with the keys 33. When the leading edges of the keys 38 have been revolved into 110 wedging contact with the inwardly sloped ends 34 of the keys 33, the holder is rigidly supported in interlocking engagement with the mounting plate 15, with the thermowafers 25 in operative contact with the pallet 26. The wedged engagement between the 115 keys 39 and the inwardly sloped ends 34 of the mounting plate will rigidly lock the holder in position against vibration of the car tending to loosen the holder.

The central portion of the end wall 38 of the holder may be provided with a punched depression 41 for centrally engaging the adjacent wafer 25. A plurality of holes 42 in the rear wall of the holder permit of the circulation of heated air from the radiator around the thermo wafers, and also permit of the insertion of a tool for forcibly rotating the holder in mounting or dismounting the same.

Ordinarily, the rear wall 38 of the holder contacts directly with the core of the radiator and conducts the heat from the radiator to the thermo wafers. When these 5 automatic shutter devices are mounted on radiators of the tubular type, the conduction of heat from the radiator core to this rear wall 38 is made difficult and somewhat uncertain owing to the relatively small surface area of the core to be engaged by the rear wall 38. The water circulating tubes 8 are typical of the tubular type of radiator, and these tubes are generally provided with a plurality of heat radiating fins 44, which 10 consist either of circular disks or flat strips of metal extending from side to side of the core and apertured for receiving the circulating tubes 8. With either construction of heat radiating fin, it will be evident that the narrow edge contact between the front of the fin and the rear wall 38 of the holder will afford a relatively small area of heat conducting contact, and this small area may be even further diminished by having only 15 two or three of these fins engage the wall 38 of the holder.

To avoid this condition, I propose providing a heat transfer plate 45 which will multiply the points of contact and the area of 20 conducting surface between the radiator core and the heat absorbing surface 38. This heat transfer plate is composed of very ductile metal, preferably soft aluminum, which can be shaped to fit the necessities of the 25 particular installation. This aluminum plate has a plurality of corrugations 46 extending transversely thereof for insertion between the heat radiating fins 44 of the core. In applying this heat transfer plate, 30 these corrugations can be forced back against the circulating tubes 8 and expanded between the fins 44 so that the plate will have multiple contact with the upper and lower sides of the fins and with the tubes 35 8. When the shutter device is applied to the radiator, after the application of this heat transfer plate, the front edges of the corrugations 46 will adapt themselves, under the pressure of drawing the shutter device 40 against the radiator core, so that each corrugation will have intimate contact with the heat absorbing surface 38 across the entire width of the latter.

It will be apparent that by making the 45 heat absorbing surface 38 separate from the mounting plate 15 there will be a lesser tendency for heat absorbed by the surface 38 from being conducted to the mounting plate 15, than if these two were integral. 50 Thus, there is a reduced tendency for heat absorbed by the surface 38 to be lost by conduction to the mounting plate 15 and its connected parts.

While I have illustrated but a single embodiment of my invention, I do not limit

myself to this specific construction, but wish to have my invention limited only by the terms and spirit of the appended claims.

Having thus described my invention, what I claim is:

1. In a thermostatic radiator shutter, the combination of a frame, a shell, a chamber between said frame and said shell, a thermostatic element in said chamber, and a closure member for said chamber, said closure member being releasable for affording access to said thermostatic element without necessitating separation of said frame and said shell. 75

2. In a thermostatic radiator shutter, the combination of a frame, a shell, means associated with said frame defining a chamber, a thermostatic element in said chamber, and a closure member for said chamber, said closure member being releasable for affording access to said chamber without necessitating separation of said frame and said shell. 80

3. In a thermostatic radiator shutter, the combination of a frame member, a shell, a thermostatic element disposed between said frame member and said shell, and a releasable closure element cooperating with said frame member for affording access to said thermostatic element from the rear of said frame member. 90

4. In a thermostatic radiator shutter, the combination of supporting means, shutter mechanism carried by said supporting means, thermostatic means for controlling said shutter mechanism, and a removable supporting member carried by said supporting means for holding said thermostatic means. 95

5. In a thermostatic radiator shutter, the combination of a supporting member, shutter mechanism, thermostatic means for controlling said shutter mechanism, a holder for said thermostatic means, and means for mounting said holder on said supporting means releasable by rotation of said holder. 105

6. In a thermostatic radiator shutter, the combination of a supporting member, a chamber defined on one side of said supporting member, thermostatic means disposed in said chamber, shutter mechanism adapted to be controlled by said thermostatic means, and a closure element releasable from the opposite side of said supporting member for affording access to said thermostatic means. 110

7. In a thermostatic radiator shutter, the combination of supporting means, a chamber defined on the front side of said supporting means, a thermostatic element in said chamber, shutter mechanism adapted to be controlled by said thermostatic element, and means permitting access to said chamber from the reverse side of said supporting means, said access affording means being releasable by rotation relative to said supporting means. 120

8. In a thermostatic radiator shutter, the combination of a mounting plate, a shell, a 125

chamber defined between said mounting plate and said shell, a thermostatic element in said chamber, shutter mechanism controlled by said thermostatic element, and a closure member releasably supported by said mounting plate for affording access to said chamber from the rear side of said mounting plate.

9. In a thermostatic radiator shutter, the combination of a mounting plate, thermostatic means disposed in the front side of said mounting plate, shutter mechanism adapted to be controlled by said thermostatic means, a holder for said thermostatic means, 10 and interlocking keys between said holder and said mounting plate releasable by relative rotation therebetween.

10. In a thermostatic radiator shutter, the combination of a mounting member, shutter mechanism, a thermostatic element for controlling the operation of said shutter mechanism, and a holder for said thermostatic element adapted to be supported by said mounting member, said holder having arcuate keys 20 thereon cooperating with arcuate keys on said mounting member.

11. In a thermostatic radiator shutter, the combination of a mounting member, shutter mechanism, a thermostatic element for controlling the operation of said shutter mechanism, a holder for said thermostatic element, and interlocking lugs on said holder adapted to cooperate with interlocking lugs on said mounting member.

35 12. In a thermostatic radiator shutter, the combination of a frame, shutter mechanism carried by said frame, a mounting plate carried by said frame, a shell receiving said frame, a chamber defined between said 40 mounting plate and said shell, a thermostatic element disposed in said chamber for controlling the operation of said shutter mechanism, said mounting plate having an opening therein for the removal of said thermostatic element from the rear of said mounting plate, and a releasable closure element 45 for said opening.

13. In a thermostatic radiator shutter, the combination of a frame, shutter mechanism carried by said frame, a plate adapted to lie in proximity to the radiator, a thermostatic element disposed on the front side of said plate for controlling the operation of said shutter mechanism, said plate having an opening therein for the removal of said thermostatic element from the rear side of said plate, and a releasable closure element 55 for said opening.

14. In a thermostatic radiator shutter, the combination of a frame, shutter mechanism

carried by said frame, a mounting plate carried by said frame, a shell receiving said frame, a chamber defined between said mounting plate and said shell, said mounting plate having an opening therein, a holder 65 supported in said opening, arcuate keys on said holder cooperating with arcuate keys on said mounting plate around said opening, and a thermostatic wafer supported by said holder for controlling the operation of said 70 shutter mechanism, said holder being releasable from said mounting plate for affording access to said thermostatic wafer by rotation relative to said mounting plate.

15. In a thermostatic radiator shutter, the combination of shutter mechanism, a pair of members separable from each other and forming a chamber therebetween, a thermostatic element in said chamber for controlling the operation of said shutter mechanism, 80 and a closure element supported by one of said members for closing one end of said chamber, said closure element being releasable for affording access to said thermostatic element without separating said members. 85

16. The combination with a radiator, of a thermally controlled shutter device for said radiator comprising thermally responsive means and heat transfer means adapted to be interposed between the radiator and 90 the shutter device for increasing the heat conductivity between the radiator and said thermally responsive means.

17. The combination with a radiator, of a thermally controlled shutter device for said 95 radiator comprising thermally responsive means, said thermally responsive means having a heat absorbing surface, and heat transfer means engaging between the fins of the radiator core and transferring heat to said 100 heat absorbing surface.

18. The combination with a radiator, of a thermally controlled shutter device for said radiator comprising thermally responsive means, a heat absorbing surface for 105 transferring heat to said thermally responsive means, a corrugated heat transfer plate adapted to have its corrugations engage between the fins of the radiator core for transferring heat to said heat absorbing surface. 110

19. The combination with a radiator, of a thermally controlled shutter device for said radiator comprising thermally responsive means, and a heat transfer plate having corrugations therein engaging between 115 the fins of the radiator core for conducting heat to said thermally responsive means.

In witness whereof, I hereunto subscribe my name this 1st day of March, 1925.

JAMES F. RALEIGH.
